UNITED STATES PATENT OFFICE.

OTTO C. GENGELBACH, OF WEST CHICAGO, ILLINOIS.

OIL BURNER.

Application filed September 5, 1924. Serial No. 736,081.

My invention relates to new and useful improvements in oil burners of the gravity type. More specifically it relates to oil burners in connection with domestic heating plants and particularly to that type which operates on the vaporizing principle.

Among the several objects of the invention are the provision of an oil burner which is constructed in a manner to promote thorough vaporization of the oil; to provide a burner with a preheating chamber whereby the oil as it is fed to the burner proper will be preheated so as to better assist in the proper vaporization thereof; to provide a burner with a cone through which the preheated oil passes to the burner and to construct the cone with vertical recesses extending inwardly toward the oil passage whereby the ignited oil within the recesses will further assist in the preheating of the oil, and to provide a burner which is extremely simple in construction and is cheap to manufacture.

With these and other objects in view which will more fully appear, the nature of the invention will be more clearly understood by following the description, the appended claims, and the several views illustrated in the accompanying drawings.

In the accompanying drawings which illustrate one form of my invention:

Figure 1 is a top plan view of a burner constructed in accordance with my invention,

Figure 2 is a front elevation thereof, the furnace being shown in section,

Figure 3 is a plan view of the burner, the air inlet arches being shown in section,

Figure 4 is a vertical sectional view through the burner and furnace,

Figure 5 is a cross sectional view taken on the line 5—5 of Figure 2, the view being enlarged,

Figure 6 is an end view of one of the flame spreaders, and

Figure 7 is a plan view thereof.

Like reference numerals designate corresponding parts throughout the several figures of the drawings.

As shown in the accompanying drawings, the furnace 1 is provided with an ash door 2 and a grate 3. Seated upon the grate are vertically disposed air inlet passages 4 and 5.

Disposed above the grate is my improved burner which includes a bowl 8 having lateral extensions 7, 7 for supporting the burner. These extensions are respectively formed with openings 9 which are in aline-

ment with the air passages. The burner 8 includes a bowl having a centrally disposed cone or tip 15 projecting upwardly from the bottom thereof. This cone is formed with a plurality of stepped portions forming a resultant series of circularly disposed depressed seats. The body portion of the cone is cut away to form a plurality of vertically disposed slots or recesses which extend inwardly from the periphery of the cone to a point adjacent the oil feeding pipe 17 which extends upwardly through the cone. These slots form the cone into a resultant series of spaced stepped portions.

Depending from the bottom of the bowl 8 and preferably extending downwardly from the periphery thereof, is a marginal flange which tapers downwardly and inwardly so as to form a supporting wall for asbestos 6, or other refractory material, which is packed within the flange and against the bottom of the bowl. Thus the flange and the refractory material cooperate to form a precombustion or preheating chamber.

The oil feed pipe 17 which leads from any suitable source of oil supply, extends upwardly through the combustion chamber, through the bottom of the bowl 8, and through the cone. The upper end of the oil pipe is located at the apex of the cone.

In operation when oil is fed through the burner by gravity, the oil will be preheated as a result of the oil pipe passing upwardly through the preheating chamber. The preheated oil flows over the apex of the cone and downwardly onto the stepped portions thereof, and also into the spaces or recesses between the stepped portions of the cone. As a result, the oil which is located in the vertical recesses of the cone will, when ignited, cooperate to further preheat the incoming oil. Thus, the oil will be preheated before it gets to the cone and immediately thereafter, and consequently combustion will be materially enhanced.

Disposed above the burner is an air supplying means which in this instance consists of a casting embodying two inverted U-shaped air supplying arches 10, 10 having their air inlet ends supported on the lateral extensions 7 of the burner and having their air outlet ends tapered as at 12 and uniting to form a common discharge opening 13 arranged concentrically with the cone of the burner, and a centrally located baffle rib 11 spaced above the tip or cone. A perforated shield is sup-

ported on the cone 15 and projects upwardly into the opening 13, the incoming air thus passing around the shield. Dampers 16 are respectively mounted in the air conduits for controlling the air as will be readily apparent.

In order to cause the flame to be directed laterally against the walls of the furnace, I have provided a pair of flame spreaders 10 which are detachably mounted and disposed in a horizontal plane on opposite sides of the air conduits. They are preferably disposed in a plane above the cone but below the upper portions of the air conduits. Each spreader 15 comprises a plate 18 having depending feet 19, and is supported on the arches 10 by means of lugs 20 fitting in recesses located in the sides of the arches, as shown in Figures 1 and 2.

20 If preferred, flame spreaders comprising waved plates 21 may be supported by lugs 22, as shown in Figures 6 and 7, which fit in the recesses in said arches.

A plurality of round steel rods 23, approximately fill that end of the pipe 17 between the valve 24 and the cone 15, as shown in Figure 5. The rods regulate the flow of oil through the pipe and also prevent the formation of scale within the pipe.

30 In operation, a small quantity of oil is first poured into the bowl 8, and this oil is then ignited to heat the cone and bowl. The valve 24 is then opened, and as this oil flows through the outlet end of the pipe 17, it strikes against the shield 14 and, with the gas formed by vaporization, is burned. The oil, while passing through the preheating chamber, is initially heated, and this preheated oil then leaves the pipe 17 and runs onto the cone 15, some of the oil passing into the vertical spaces of the cone at points close to the pipe 17. This oil being burned in these spaces causes the upper end of the pipe to be heated and consequently this action serves to 40 further preheat the oil. This double preheating of the oil effects a quick and highly efficient combustion action which is most desirable in this type of burner.

It is of course to be understood that the 50 details of structure and arrangements of parts may be variously changed and modified without departing from the spirit and scope of my invention.

What is claimed is:—

55 1. The combination of an oil burner having a grate, of a burner bowl supported thereon, an oil spreading and vaporizing member in the bowl, means for feeding oil to the spreading and vaporizing member, and a preheating 60 chamber formed as a part of the bowl and packed with refractory material, said feeding means passing through the chamber, whereby the incoming oil will be preheated to assist vaporization thereof.

65 2. In an oil burner, the combination of a

burner bowl, said bowl comprising a casting having an oil spreading and vaporizing member integrally formed therewith and positioned centrally in the bowl, an oil supply pipe leading to said member, and a preheating chamber below said bowl and also integrally formed therewith, said chamber adapted to be packed with refractory material which when heated will serve to preheat the oil supply pipe to assist vaporization. 70

3. In an oil burner, a bowl, a tip formed with depressed stepped portions integral with said bowl, said depressed stepped portions being arranged in groups spaced apart, a conduit extending through said bowl and tip, and air delivery means associated with said tip, said delivery means comprising a baffle rib spaced above said tip. 75

4. In an oil burner, a bowl, a tip formed with depressed stepped portions arranged in groups spaced apart and rising centrally from said bowl, a conduit extending through said bowl and tip, and air delivery means associated with said tip. 80

5. In an oil burner, the combination with a bowl, of a cone extending upwardly from the bottom of the bowl, a preheating chamber disposed below the bowl and supported thereby, and means for directing oil upwardly through the preheating chamber and thence 90 through said cone. 95

6. In an oil burner, the combination with a bowl, of a cone extending upwardly from the bottom of the bowl, a preheating chamber disposed below said bowl and comprising an annular wall attached to the bowl, the space within the wall being filled with refractory material, and means for directing oil upwardly through the refractory material of the preheating chamber and thence through 100 said cone. 105

7. In an oil burner, the combination with a bowl, of a cone extending upwardly from the bottom of the bowl, a preheating chamber disposed below said bowl and comprising an annular wall attached to the bowl, the space within the wall being filled with refractory material, means for directing oil upwardly through the refractory material of the preheating chamber and thence through said cone, and a pair of inverted U-shaped air supplying arches having air inlet ends exterior of the bowl and having air outlet ends uniting in a common air discharge opening located directly above the cone. 110

8. In an oil burner, the combination with a bowl, of a cone extending upwardly from the bottom of the bowl, a preheating chamber disposed below said bowl and comprising an annular wall attached to the bowl, the space within the wall being filled with refractory material, means for directing oil upwardly through the refractory material of the preheating chamber and thence through said cone, a pair of inverted U-shaped air supply- 120

ing arches having air inlet ends exterior of the bowl and having air outlet ends uniting in a common air discharge opening located directly above the cone, and horizontally disposed flame spreaders respectively arranged on opposite sides of and supported by the air supplying arches.

9. In an oil burner, the combination with a bowl, of a cone extending upwardly from the bottom of the bowl, a preheating chamber disposed below the bowl and supported thereby, and means for directing oil upwardly through the preheating chamber and thence through said cone, said cone being provided with a plurality of vertically disposed slots extending inwardly from the periphery to a point adjacent the oil feeding means.

10. In an oil burner, the combination with a bowl, of a cone extending upwardly from the bottom of the bowl, a preheating chamber disposed below the bowl and supported thereby, and means for directing oil upwardly through the preheating chamber and thence through said cone, said cone being formed with a plurality of horizontally dis-

posed circular steps and with a plurality of vertically disposed slots extending inwardly from the periphery to points adjacent the oil feeding means.

11. In an oil burner, the combination with a bowl, of a cone extending upwardly from the bottom of the bowl, and means for directing oil upwardly through the bowl and cone, said cone being provided with a plurality of vertically disposed slots extending inwardly from the periphery to a point adjacent the oil feeding means.

12. In an oil burner, the combination with a bowl, of a cone extending upwardly from the bottom of the bowl, and means for directing oil upwardly through the bowl and cone, said cone being formed with a plurality of horizontally disposed circular steps and with a plurality of vertically disposed slots extending inwardly from the periphery to points adjacent the oil feeding means.

In testimony that I claim the foregoing as my own I have hereto affixed my signature.

OTTO C. GENGELBACH.
